DISPLAY RACK

Maurice Cohen, Miami, Fla.

Application February 20, 1957, Serial No. 44,930

Term of patent 14 years

(Cl. D80—9)

Fig. 1.

Fig. 2.

Fig. 1 is a view in perspective of the display rack, showing my new design; and

Fig. 2 is a top plan view thereof on a reduced scale with the base omitted for convenience of illustration.

The dominant features of my design reside in the full line portions of the drawing.

I claim:

The ornamental design for a display rack, as shown and described.
